UNITED STATES PATENT OFFICE

1,924,036

ELECTRICAL CONNECTER

William H. Harrington, West Hartford, Conn., assignor to The Arrow-Hart & Hegeman Electric Company, Hartford, Conn., a Corporation of Connecticut

Application January 15, 1929. Serial No. 332,628

5 Claims. (Cl. 173—322)

My invention relates to electrical connectors and more particularly to outlet or plaster box covers and grounding means associated therewith for grounding all the non-current carrying 5 metallic parts.

It is an object of my invention to make an improved and inexpensive heavy duty current installation.

Another object is to make an improved plaster 10 or outlet box cover.

Another object is to provide means for grounding the cable strain relief fitting of a plug member which co-operates with a receptacle member in the outlet or plaster box.

15 Other objects will appear as my invention is described in connection with the accompanying drawing in which

Fig. 1 is a side elevation of my improved plug and receptacle invention shown with the plug re-20 moved from the receptacle.

Fig. 2 is a side elevation view of my invention as shown in Fig. 1, but with the outer metal parts shown in a section taken on line 2—2 of

Fig. 3 which is a plan view of my improved 25 plug and receptacle with the plug inserted and permanently secured. The plaster box cover is shown in dotted lines.

Referring to the drawing a plug body 1 of insulating material has three contact fingers 2 projecting therefrom, which co-operate with receptacle contacts (not shown) located in openings (not shown) in a conventional type of porcelain or other insulating receptacle 3. These fingers are so arranged in angular relation to each other 35 that they may be pushed into the plug receptacle 3 only when the plug and receptacle are in a certain position, thus preventing reversal of the polarity of the current in the appliance supplied through the receptacle, by improper insertion of 40 the plug.

A cover 6 formed of a square metal plate with rounded corners and a round central aperture 16 surrounded by a flange 13 formed integral with and turned up from the plate is adapted to fit in 45 the top of a conventional outlet box 15, to which the cover may be held by screws 7 threaded in in-turned ears 17 on the box and through holes 18 in the cover. To facilitate assembling the cover on the box the holes 18 are elongated and en-50 larged at one end so that the heads of the securing screws 7 may pass therethrough and so that upon clockwise rotation of the cover the small end of the hole will be caught under the screw head and the cover thus will be held on the outlet 55 box.

The receptacle 3 is supported in a U saddle 4 which is held securely on outlet box cover 6 by screws 8 threaded in out-turned ears 10 of the saddle and also threaded in out-turned lugs 12 of the outlet box cover flange 13. The saddle 4 60 lies in the plate aperture 16 and hence the receptacle 3 supported thereby lies in the aperture and outlet box.

To improve the appearance and to protect the live parts of the apparatus a face plate 20 is secured to the outlet or plaster box cover 6 by screws 21 threaded in out-turned ears 22 on the plaster box cover flange 13. The face plate has a round central aperture registering with the aperture 16 of the outlet box cover in order that 70 the head of the porcelain receptacle may project therethrough.

Adjacent the edges of the aperture in the face plate are two diametrically opposed slots 23 into which tongues 24 downwardly projecting from 75 the ring 25 of a cable strain relief fitting 26 on the plug 1, are adapted to extend. Beneath the slots 23 and in the path of movement of the tongues are downwardly bent contact fingers 26' secured in contact with the under side of the 80 face plate 20. As the tongues pass through the slots they rub against and make contact with the contact fingers.

Since it is customary to ground the outlet box, 85 it will now be apparent that by using my above described construction all the non-current carrying metal parts, namely the outlet box, its cover, the face plate and the strain relief fitting, will be grounded. Specifically, cover 6 is grounded by its connection with the outlet box, the face 90 plate is grounded by its connection with the cover and the strain fitting is grounded by its tongues contacting with the fingers of the face plate.

If it is desired to maintain the plug permanent-ly in current carrying condition, the strain relief 95 fitting may be formed with diametrically opposed laterally extending arms 28 integral therewith. These arms may have apertures in their ends registering with the screw hole apertures of the 100 face plate securing screws 21, so that these screws may serve to secure both the plug and face plate to the outlet box cover.

When the apparatus is assembled as described 105 and as shown in Figure 2 and with the outlet box 15 depressed in the wall as usual, plaster may be moulded about the flange 13 of the outlet box cover making a neat and finished looking construction.

Many changes and modifications within the 110

scope of my invention will occur to those skilled in the art.

I claim:

1. An electrical connector comprising a plug, a plug receptacle, a grounded face plate having a finger thereon, a strain relief fitting on said plug having means thereon co-operating with said finger to ground said fitting.
2. An electrical connector comprising a grounded face plate, a connector plug and socket therefor, a strain relief fitting on said plug, a tongue on said fitting for grounding it.
3. An electrical connector comprising a connector plug, a receptacle therefor, a grounded face plate associated with said receptacle, slots in said plate with fingers therebelow and a strain relief fitting on said plug having tongues adapted to project through said slots and contact with said fingers to ground said fitting.
4. An electrical connector comprising a cover for an outlet box or the like formed of an apertured plate having a flange surrounding the aperture, a saddle supported from said flange and depending in said aperture, a receptacle housing contacts and supported by said saddle, an aper-

tured face plate secured to said cover, said plate having slots therein with contact fingers therebelow, in combination with a connector plug having contacts co-operating with said receptacle contacts, a strain relief fitting on said plug, said fitting having tongues adapted to slide in said slots and to co-operate with said fingers whereby the fitting may be grounded, said fitting also having projecting arms whereby it may be fixedly secured to said face plate.

5. An electrical connector comprising an outlet box, a cover therefor formed of an apertured plate having a flange surrounding the aperture, a saddle supported from said flange and depending in said aperture, a receptacle housing contacts and supported by said saddle, an apertured face plate secured to said cover, said plate having slots therein with contact fingers therebelow, in combination with a connector plug having contacts co-operating with said receptacle contacts, a strain relief fitting on said plug, said fitting having tongues adapted to slide in said slots and to co-operate with said fingers whereby the fitting may be grounded.
